(57) CLAIM

The ornamental design for a shopping bag handle, as shown and described.

DESCRIPTION

The product is a handle for removably attaching to the carrying straps of at least one shopping bag thereby providing an enhanced grip for carrying said bag.

Utility patent application Ser. No. 11/811,540, titled “Shopping Bag Handle”.

FIG. 1 is a front elevation view of the shopping bag handle; and,

FIG. 2 is an left end elevation view of the shopping bag handle.
